 Matthew W. Mitchell(57) **CLAIM**

The ornamental design for a fabric swatch, as shown and described.

DESCRIPTION

FIG. 1 is a front isometric view of the fabric swatch showing our new invention;

FIG. 2 is a front view thereof;

FIG. 3 is a rear view thereof;

FIG. 4 is a top plan view thereof, the bottom plan view being a mirror image thereof;

FIG. 5 is a right side view thereof, the left side view being a mirror image thereof; and,

FIG. 6 is an enlarged isometric detail view of area 6 circumscribed within FIG. 1.

The broken lines on the edges of the drawings depict portions of the fabric swatch that form no part of the claimed design. The broken line circumscribing part of the design within FIG. 1 and around the FIG. 6 drawing indicate the area of the enlarged detail and form no part of the claimed design.
